UNITED STATES PATENT OFFICE.

PAUL W. SIEURIN, OF GOTTERBORG, SWEDEN.

TACKLE.

Application filed November 9, 1925, Serial No. 67,788, and in Sweden December 5, 1924.

My invention relates to tackles especially as used on ship board on davits or the like in order to simplify the operation and use of the tackles especially when hoisting the 5 blocks after having lowered the life boats.

Frequently life boats on board ships are placed in sets of two or more on top of each other, in which case the same couple of davits is provided to handle several life 10 boats. After having launched the first life boat the tackles have to be hoisted up to be used for launching the next life boat. It most frequently happens that the tackles thereby swing around and the rope parts become twisted, so that all hoisting is 15 obstructed. It also happens that the lower pulley block or blocks turn over between the rope parts twisting them together.

In order to obviate said troubles the present invention has been made. It consists 20 therein that one of the rope runs of each tackle runs through a deflector block, the block rope being so arranged that it can be hauled sideways so that said rope run is deflected away from the others.

An important application of the invention can be made by carrying each deflector block 25 controlling rope over a sheave, properly provided at the inward gunwale of the life boat, and further along the side of the boat forward and past the stern at that end of the boat which is lifted by the tackle and then to the davit or to a place in its proximity. In such case there should of course exist 30 some means for hauling in the deflector block rope or shorten it, so that not only one of the rope runs can be carried outward and thus lift the boat somewhat from its supports, but also during a further hauling in 35 of the deflector block rope the life boat can be operated to swing outwardly.

My improved arrangement is illustrated 40 on the accompanying drawing, in which

Fig. 1 is a side elevational view of a life boat and supporting davits showing my improved tackle arrangement and control;

Fig. 2 is a plan view of the same, and

Fig. 3 shows a modified arrangement.

In davits 1 a life boat 8 is suspended by 45 means of tackles 2 and is also standing on supports 11. One of the runs 12 of each of the tackles 2 runs through a deflector block 3, the controlling rope 4 of which in the 50 shown embodiment runs over a block 5 fastened to the boat 8 by means of any suitable device 6, which device is detachable and

preferably so arranged that it is fastened only by means of taps or the like to the gunwale. The ropes 4 are further carried to tackles 7 and 7' respectively, and then by 60 means of ropes 9 to the respective davit 1, where such ropes are fixed.

Before the life boat is swung out all the parts are in a state of rest, the tackles 2 being hauled tight and their runners made 65 fast to some keel or cleat device preferably provided in the life boat. When the life boat is to be launched the runners of the tackles 7 are hauled whereby the corresponding rope 4 is tightened and the part 12 at the right 70 hand tackle is carried outward by the deflector block 3 and stretched, thereby lifting this end of the boat somewhat. The runner 12 can not, however, be carried outward any great distance before the resistance will be 75 come so great that the strain in the rope 4, the tackle 7 and the rope 9 forces the boat over board with the stern past its davit. Then the runner of the tackle 7' is hauled in and the same operation is repeated with the 80 other end of the boat. The boat can then be lowered somewhat by means of the tackles 2 and be manned. During the further lowering the device 6 is released from the gunwale and thereby also from the tackles 7 85 and 7'.

If it appears, after launching the boat and releasing it from the tackles, that the tackles tend to twist, this can be obviated by carrying the rope runners 12 still further outward 90 by further hauling in the tackles 7, 7'. In order to prevent the lower tackle blocks from turning around between the rope runners these blocks are preferably so designed that their point of gravity comes comparatively 95 low. During the hoisting of the blocks the runners of the tackles are thus prevented from being twisted partly on account of the fact that the deflector blocks keep one of the runners of the respective tackle away from 100 the others, and partly on account of the keel devices preventing the lower blocks from turning over.

The deflector blocks can be used independently of the swinging out tackles 7 and 105 7'. This is shown in Fig. 3 where the tackle 13 connects the ropes 4 extending from the deflector blocks 3 which engage each a runner of the respective hoisting tackle 2. By means of the tackle 13 the 110 deflector blocks are caused to deflect the runners 12 to prevent twisting of the tackles

2 and at the same time to operate these 5 tackles to raise the boat. Such raising is in conjunction with swinging movement of the boat controlled by the tackles 7 and 7'. 50

5 From this invention the advantage will be derived that the ship's deck will be free from all encumbrance directly after the swinging 10 out of the boats. Thus the boat supports 11 can be made detachable and fixed only by means of pins in the deck. Devices for 15 launching the boats can be tied to folding ring-bolts. In this way the deck can be freed in an instant from all protruding objects so that nothing obstructs the passage 20 and an easy embarkation. During the embarkation the valuable advantage is obtained 25 that the life boat is held very steady by the tackles 7, 7'. Furthermore, an additional staying of the boat is obtained by placing a rope or the like in a well known manner 30 from one of the gunwales of the boat down below the middle of the boat on its outside and thence in to a fastening on the deck. 35

Having described my invention, I claim as 40 follows:—

1. In combination, two adjacent suspended 45 tackles, a deflector block engaging one of the rope runners of each tackle, and means for hauling said deflector blocks toward each 50 other whereby to deflect the rope runners. 55

2. In combination, davits, a life-boat, 60 tackles suspending said boat from said davits, the ends of the ropes of said tackles being secured, a deflector block engaging one 65 of the rope runners of each suspended tackle, means for hauling said deflector blocks toward each other to cause deflection of the 70 engaged runners and operation of the suspended tackles to lift the boat. 75

3. In combination, davits on board ship, 80 a life-boat, tackles for suspending said boat from said davits, the ends of said tackle ropes being secured, a deflector block receiving one of the rope runners of each suspending 85 tackle, means for hauling said deflector blocks toward each other to cause deflection

of said engaged rope runners and operation of the suspended tackles to raise the boat, and means for swinging said boat when thus raised by said suspending tackles. 50

4. In combination, a pair of davits on ship board, a life boat, suspension tackles for suspending said boat from said davits, a set of pulley-blocks on the inside of said boat positioned at substantially the middle thereof, a tackle extending from each davit around the adjacent end of the boat and along the inner side thereof, a deflector rope extending from each of said tackles through one of said pulley-blocks, a deflector block 60 at the free end of each deflector rope receiving one of the rope runners of the respective suspension tackles, operation of either one of said swing controlling tackles causing operation of the respective deflector blocks to 65 deflect the rope runner engaged thereby and to cause the respective suspension tackle to raise the respective end of the boat. 70

5. In combination, a set of davits on ship board, a life-boat, suspension tackles suspending said boat from said davits, a deflector block 75 engaging one of the runners of each of said tackles, swinging tackle mechanism associated with each davit and the adjacent end of said boat for swinging such end, and means whereby operation of either of said controlling tackles will pull the respective deflector block to cause deflection of the engaged rope runner and operation of the suspension tackle to raise such end of the boat. 80

6. In combination, a set of davits, a life-boat, suspension tackles for suspending said boat, a deflector rope engaging one of the runner ropes of each of said suspension tackles, and a tackle connecting the outer 85 ends of said deflector ropes for drawing said ropes to cause deflection of the engaged runner ropes whereby twisting of the suspension tackles will be prevented. 90

In witness whereof, I hereunto subscribe my name this 14th day of October, 1925.

PAUL W. SIEURIN.
